UNITED STATES PATENT OFFICE

ALBERT W. METZNER, OF DAYTON, OHIO, ASSIGNOR TO JOHN Q. SHERMAN, OF DAYTON, OHIO

PROCESS OF MANIFOLDING

Application filed September 28, 1927. Serial No. 222,666.

My invention relates to the forming of manifolding copies in a series of superimposed forms or pieces of paper which shall be perforated as well as imprinted with a colored impression, so as to be entirely safe against alterations.

It is my object to employ in the marking of manifold copies a type face or reciprocating perforating pin which penetrates all of the sheets upon which the manifold impression is to be made, and to pigment or color the walls of the perforate holes made by the pin or type face by means of particles of color dislodged, by the operation of perforating, from the backs of the forms next above the ones to be colored.

My object is to do away with carbon paper, which is costly and is a nuisance to handle because of its tendency to smudge, wear out, make indistinct copies and limit the number of copies that can be manifolded. Instead of this, and instead of using manifolding cloth or printing cloth, I employ a kind of coated paper which has a particular quality that suits my process. This paper is coated on the side which will lie next above a piece of paper to be marked with a non-smudging hard coating, and contains those elements which give a permanent like finish to the paper. The coating is preferably of such a type that it will be brittle to a certain degree, and should have a color which contrasts markedly with the color of the piece of paper that is to be marked. In the paper trade, a stock grade of this type of paper is known as glazed coated paper, and is readily obtainable, and demonstrates the process.

I have found that if such a permanently coated paper or other types of color coated paper where the color coat is not smudgy or easily dislodged, is employed, that I can by using a perforating pin or a type face formed of pins, readily dislodge sufficient of the color coating from an upper coated web to pigment the walls of the holes made in the lower web by the perforating element. While not as brightly pigmented as were carbonized paper used, or a printing ribbon or the like, the color is not smudgy at all, and while it can be erased, it will remain

quite permanently about the perforations so as to color them and render the reading of them easy.

The best mode of practicing my invention is to use a paper coated on the underside with color and left white or with a pale color on the top side, with the top side imprinted with whatever form is being used. It is not practical in ordinary industrial uses to employ manifold slips and forms which are coated with carbon paper finish on the underside because of the smudging of anything with which such a form comes in contact. With the use of the special coating or any other relatively permanent color coating, I am enabled to do away with the interleaving of any copy paper whatever between the forms in a manifolding machine, and it also enables me to make many more copies at one writing.

The most expensive element in the use of manifolding machines to-day is not the printed paper issued thereby, but the carbon paper which is used. Also, when a large number of forms must be made as copies, there will have to be twice as thick a bundle for the type to act upon as would be required, were it practical to use form sheets which are coated on the back with removable carbon.

Thus my invention eliminates the cost of carbon sheets, makes it practical to form a larger number of copies at one writing than in the past, and it makes good legible copies throughout.

I accomplish my objects by that certain process to be pointed out in detail, and for the use of which a typical mechanism will be shown and described.

In the drawings:-

Figure 1 is a side elevation of a manifolding machine, in this instance an Elliott Fisher manifolding typewriter.

Figure 2 is a plan view showing the paper laying on the platen of the machine.

Figure 3 is a detail view of the pin faced type which are used by me.

Figure 4 is a detail of the type body abutment plate.

Figure 5 is a view of letters showing the

nature of the imprint made in accordance with my process.

Figure 6 is a view on an enlarged scale to illustrate graphically the manner in which my process operates.

My process can be employed with a typewriter having type faces formed of pointed pins spaced from each other and arranged in the shape of a desired character or letter.

It can also be employed with a stylus having a reciprocating point that is operated somewhat after the fashion of a flexible shaft dentist's tool.

I have shown, however, only the typewriter mechanism which will suffice to explain the nature of my invention.

I have illustrated a typewriter 1 mounted to move to and fro and forward and back on a frame 2. A storage roll for manifold paper webs, such as printed form, is shown at 3. This paper will preferably be coated on the back with a color coat. I have illustrated one of the webs at 3^a, as having a color coating 3^b. As stated, this color coating should be of non-smudging type, and preferably should be a coating of a color which strikingly contrasts with the printed form face of the paper, or if not printed, the color of the face of the paper upon which writing or typing is to be done.

The typewriter will have its type arms as at 4 equipped at the ends with pins 5 driven into the ends, which pins carry type bodies 6. The type bodies 6 have each a set of pins 7 which are sharp pointed and arranged in the shape of the desired character or letter. They will normally be held in the type body by means of Babbitt metal.

Mounted on the typewriter and moving therewith I provide an abutment plate 8 against which the type bodies will strike, said abutment plates being arranged to overhang the usual ribbon guide of the manifolding machine. The pins of the type are provided clearance by a notch 8^a in the plate.

The paper is laid across the platen of the machine and held down as by the usual clamp bar 9 of the Elliott Fisher machines, and the usual ribbons 9^a employed for the top web.

As the typewriter is operated in the usual manner, striking the selected type arms down against the paper, the pins will penetrate all of the forms. Since the forms have on their backs the color coatings noted, the result of the pins passing through is to dislodge, as indicated at 7^a, and to lift off a little patch of the color coating and deposit it about the walls of the perforated hole which the pin makes in the underlying web. This action applies alike to all forms which are employed.

Having thus described my invention, what I claim as new and desire to secure by Letters Patent, is:—

1. A process for manifolding, which consists in assembling together a pile of paper webs of which the back of an uppermost web is coated with a non-smudging color, and passing a pin through the pile, with the result of dislodging particles of the color coating and depositing them around the walls of the hole perforated in the paper next beneath said coating. 70

2. A process for manifolding, which consists in assembling together a pile of form strips of paper, said strips having their backs coated with a non-smudging color, and passing a pin through the pile, with the result of perforating all of the webs, and dislodging from the back coatings of each web particles of color which surround the walls of the holes in the webs lying next beneath. 80

3. A process for manifolding, which consists in assembling together a pile of paper webs of which the back of an uppermost web is coated with a non-smudging color, and passing a pin through the pile, with the result of dislodging particles of the color coating and depositing them around the walls of the hole perforated in the paper next beneath said coating, said color coating being formed as a relatively hard coating. 85

4. A process for manifolding, which consists in assembling together a pile of paper webs of which the back of an uppermost web is coated with a non-smudging color, and passing a pin type face through the pile, with the result of dislodging particles of the color coating and depositing them around the walls of the hole perforated in the paper next beneath said coating. 95

5. A process for manifolding, which consists in assembling together a pile of form strips of paper, said strips having their backs coated with a non-smudging color, and passing a pin type face through the pile, with the result of perforating all of the webs, and dislodging from the back coatings of each web particles of color which surround the walls of the holes in the webs lying next beneath. 100
